DECORATIVE ESCUTCHEON PLATE FOR A LOCK

Richard H. Arbib, New York, N. Y., and Robert S. Quandt, Levittown, Pa., assignors to Independent Lock Company, Fitchburg, Mass., a corporation of Massachusetts

Application November 4, 1954, Serial No. 32,957

Term of patent 14 years

(Cl. D50—6)

Figure 1 is a plan view of a decorative escutcheon plate for a lock showing our new design;

Figure 2 is a section on the line 2—2 of Figure 1;

Figure 3 is a section on the line 3—3 of Figure 1.

We claim:

The ornamental design for a decorative escutcheon plate for a lock, substantially as shown.
